(57) **CLAIM**

The ornamental design for a desktop cable cover, as shown and described.

DESCRIPTION

FIG. 1 is a top perspective view of a desktop cable cover showing our new design;

FIG. 2 is a bottom perspective view thereof;

FIG. 3 is a left side view thereof, the right side view being a mirror image;

FIG. 4 is a back elevation view thereof;

FIG. 5 is a front elevation view thereof;

FIG. 6 is a top plan view thereof;

FIG. 7 is a bottom plan view thereof; and,

FIG. 8 is a perspective view thereof, shown in environmental use.

The broken lines in FIG. 8 depict environmental subject matter only and form no part of the claimed design.
